(57) **CLAIM**

The ornamental design for a nursing cover configured for covering a baby while nursing or while the baby is in a baby seat, as shown and described.

DESCRIPTION

FIG. 1 is a front perspective view of the nursing cover; FIG. 2 is a back perspective view of the nursing cover; FIG. 3 is a side perspective view of the nursing cover; FIG. 4 is a front perspective view thereof shown in a first environment of use; FIG. 5 is a front perspective view thereof shown in alternate option in the first environment of use; FIG. 6 is a front perspective view thereof shown in second environment of use; and, FIG. 7 is a front perspective view thereof shown in alternate option in the second environment of use. The broken lines illustrating the environment of the nursing cover form no part of the claimed design.

1 Claim, 5 Drawing Sheets
